UNITED STATES PATENT OFFICE.

CHARLES HENRY FROST, OF PASADENA, CALIFORNIA.

SEWER OR STORM-DRAIN CONSTRUCTION AND METHOD OF FORMING THE SAME.

1,093,612.

Specification of Letters Patent. Patented Apr. 21, 1914.

Application filed June 3, 1912. Serial No. 701,456.

To all whom it may concern:

Be it known that I, CHARLES H. FROST, a citizen of the United States, residing at Pasadena, in the county of Los Angeles and 5 State of California, have invented a new and useful Sewer or Storm-Drain Construction and Method of Forming the Same, of which the following is a specification.

One of the objects of the invention is to 10 construct a sewer or drain of circular form, and entirely of bricks of such formation that it will possess that amount of rigidity which is necessary to enable it to successfully resist the strains to which sewers and drains 15 are ordinarily subjected when laid many feet under ground, and, in addition, it may be laid with a minimum amount of labor, and at a low cost.

Another object of the invention is to construct a sewer or drain of the type referred 20 to of bricks of such shape as to permit the bricks to be laid, by hand labor, in the formation of a circular sewer without an inside mold or form. In order to accomplish 25 this object in the manner contemplated by the present invention, I employ bricks of uniform size and shape in cross-section, each having a rib on one side and a groove on the other side, and the bricks being of 30 greater width than thickness and when laid side by side the rib of one brick will fit within the groove of the next adjacent brick. The particular manner in which these bricks are laid to obtain the benefits and accomplish 35 the objects of the invention will be hereinafter fully explained.

Referring to the drawings: Figure 1 is a perspective view of a portion of the sewer. Fig. 2 is a perspective view of four bricks, 40 showing one method of construction. Fig. 3 is a perspective of another form of brick.

In carrying my invention into effect, I form a rib on one face of the brick and a groove on the opposite face of the brick, so 45 that the bricks when laid together, will interlock with each other, the rib of one brick interlocking in the groove of the adjoining brick. I also form the brick tapering, the walls having the ribs and grooves converging 50 toward the center of the sewer. In the drawings, 1 designates the brick having a rib 2 on one face and a groove 3 on the opposite face.

The brick shown in Fig. 2 is formed by 55 forcing clay through a die, the contour of

which is the cross-sectional shape of the brick, thus producing a bar with a rib on one side and a groove on the opposite side. This bar is then severed at suitable lengths to form the proper length for the bricks, 60 this being called the end-cut brick.

In laying the sewer, mortar is laid between the bricks in the usual manner, so that when the sewer is constructed, the bricks are firmly tied together by the mortar 65 as well as by the interlocking joints which prevent the brick from falling in, and form an extremely rigid and strong construction. A sewer constructed in this manner is much stronger than one joint with ordinary bricks 70 laid in two layers and obviously, the expense both of labor and material is very much less. In building up the sewer the bricks are laid regularly, one against the other, with the rib of each brick projecting 75 into the groove of the adjoining brick, and only the key-brick at the top requires slipping in endwise. The lower half of the arch is first built for a considerable distance, and every alternate brick in each transverse row 80 projects, say, half a length, so as to "break-joint" with those in the adjacent rows, the workmen gradually building up the arch toward the formation of a complete ring at the beginning of the sewer, and working 85 thence along on a gradual incline, as shown in Fig. 1. As each brick is laid to form the upper arch the bricks to form the succeeding courses are added to the lower arch, thus giving the mortar time to set in the upper arch. The fact that the bricks are of 90 greater width than thickness, and, moreover, also have interlocking ribs and grooves, permits them to be laid up to the last two bricks to complete the upper arch, which 95 last two bricks are finally pushed in endwise to complete the first ring of the sewer. Said first ring may, therefore, be completed by using the shape of brick herein described, and by proceeding in the above-described 100 manner, without necessitating an inside form or support for the bricks of any kind whatsoever. After the first row of bricks extends completely across the top of the arch the upper segment of the arch is readily extended forward as the first row will interlock with and hold the next row, and each succeeding row, as it is added, will be held in like manner until the entire arch is completed. In addition to their mechanical 105 110

function of interlocking the bricks together, the interlocking rib and groove greatly assist in retaining the mortar in place.

The bricks may be of a size deemed best, according to the size of the sewer. Thus for a large sewer with thick walls, large bricks may be used, and for a smaller sewer with thinner walls, smaller bricks may be used.

In Fig. 3 is shown a slightly modified form of brick in which a plurality of ribs 2' are shown on one side of the brick and a plurality of grooves 3' are shown on the opposite side. In this form, as shown in the preceding forms, the ribs on one side of each brick fit into the grooves on the adjoining side of the next brick. In either form the radial dimension of the brick is greater than its circumferential dimension. This is highly important because it provides an inherently stable structure which is non-collapsible.

It is obvious that the structure herein disclosed may be employed for storm drains as well as for sewers.

25 What I claim is:

1. An arched conduit of circular form composed entirely of bricks all of which are of the same dimensions in cross-section, and each brick having a groove on one side and a rib on the other, the rib in each brick fitting in the groove of the adjoining brick to prevent the bricks from falling apart, the width of each brick being substantially greater than its thickness, and the bricks in each transverse row of the conduit arranged to break joint with the bricks in the succeeding row, said bricks being first laid to

form a portion of the lower half of the arch, and then laid to close the upper part of the arch for one row by laying the bricks on a gradual incline longitudinally of the arch, and as soon as one row of bricks is carried across the first arch the upper segment is extended forwardly, and the operation continued.

2. The method of forming a conduit of circular form in cross-section entirely of bricks of identical size in cross-section and having each a rib on one side and a groove on its other side and its width considerably greater than its thickness, consisting in first building the lower half of the arch for a considerable length by laying said bricks in mortar side by side in transverse rows in which the bricks in each row break joint with those in each succeeding row, then closing the upper part of the arch by laying the bricks on a gradual incline longitudinally of the arch with one brick in advance of the other so that the lower and forward bricks interlock with and support the adjacent and upper bricks, and as soon as one row of bricks is carried completely across the top of the arch extending the upper segment of the arch forwardly, and continuing the operation throughout the conduit.

In testimony whereof, I have hereunto set my hand at Los Angeles, California this 28 day of May 1912.

CHARLES HENRY FROST.
